UNITED STATES PATENT OFFICE.

HENRY S. WOODRUFF, OF EAST ORANGE, NEW JERSEY, ASSIGNOR TO GENERAL MOTORS CORPORATION, OF DETROIT, MICHIGAN, A CORPORATION OF DELAWARE.

WINDING MACHINE AND METHOD.

Application filed March 14, 1924. Serial No. 699,234.

This invention relates to winding and is herein exemplified as a method and apparatus for winding a strip of metal into helical form to be afterward cut up into hollow 5 cylindrical rollers for bearings.

Hitherto, rollers have been made by winding a strip of metal on a mandrel, a rotating chuck holding one end of the strip and being advanced by a screw to pull the strip 10 through a fixed guide and wrap it around the mandrel. In such machines, the initial coils are imperfect, involving waste, and the length of a coil is limited by the length of the mandrel or by the traverse of the chuck. 15 In other machines that use rolls, it is necessary to form the initial coils by hand or by apparatus distinct from the apparatus which continues the operation, involving a considerable loss of time in changing from one 20 device to the other.

An object of this invention, therefore, is to provide a method and apparatus for winding rollers or the like that will avoid the above disadvantages. In accordance 25 with one feature, a coil of unlimited length can be automatically formed without the necessity for any preliminary operation on the initial coils. This is accomplished by feeding a strip endwise along a helicoidal face to a series of winding instrumentalities which progressively bend the strip around a core. Prior winding machines have required large floor space and were complicated and expensive, this being due in part 30 to the necessity for a long mandrel and operating means therefor.

Another object is to provide a simple, compact and less expensive machine and this is accomplished by eliminating the long 40 mandrel and coiling the strip around a short stationary core by a series of driven rollers. Hitherto, in winding a comparatively thick strip around a mandrel of small diameter, difficulty has arisen due to the tendency of 45 the strip, which is stretched on its outer side and compressed on its inner side, to curl upwardly at the edges and another object is to avoid this defect. In accordance with this feature, the strip is fed between a 50 convex and a concave roll driven at different speeds and delivered to winding rolls driven at a faster speed thereby straining the strip

and giving it a cross section which has a predisposition to form a smooth hollow cylinder when helically wound and counter- 55 acting the tendency to curl.

To these ends and also to improve generally upon devices of the character indicated my invention consists in the various matters 60 hereinafter described and claimed.

Referring to the drawings, Figure 1 is a plan view of the machine.

Figure 2 is a front elevation.

Figure 3 is a plan view of one of the 65 winding heads.

Figure 4 is a front elevation of parts shown in Figure 3 with a portion of the casing removed.

Figure 5 is an end elevation of Figure 4.

Figure 6 is an end elevation of the wind- 70 ing head.

Figure 7 is a section on the line AA of Figure 6 with some parts omitted.

Figure 8 is a section on the line BB of 75 Figure 6 with some parts omitted.

Figure 9 is a section on the line DD of Figure 6 with some parts omitted.

Figure 10 is a vertical section through some of the driving mechanism and

Figure 11 is a perspective view of the 80 work guide.

The numeral 10 indicates a frame or stand supporting two winding heads enclosed in casings 12 and 14, one head being arranged to wind a strip of metal right handed and 85 the other winding it left handed. The strip S of material to be wound is introduced between a lower feed roll 16 and an upper feed roll 18, the lower feed roll having a convex periphery and the companion roll having a 90 concave periphery and being driven a little faster to iron out the strip and cause it to take a cross-section which will facilitate its winding into helical form. Feed rolls of this form also get a good grip on the stock 95 even if it is smooth, and knurling or roughening of the stock can be dispensed with. The lower feed roll is fixed to a shaft 20 journalled in boxes in the casing 12 and the upper feed roll is fixed to a shaft 22 journalled in a pivoted box at one end and in a 100 slide block 24 at the other. The block 24 is slideable vertically to a small extent in a slot in the end wall of the casing, being

guided on one side by a cap 26 closing the side of the casing and fastened thereto by screws. The block 24 carries a vertical stud 28 abutting at its upper end against the middle portion of a flat spring bar 30, pivoted at 32 between lugs 34 of the end cap. A stud 36 fixed to the casing projects upwardly through the end of the spring bar and is threaded for the reception of a knurled collar 38 for the purpose of adjusting the distance between the feed rolls to get the proper grip.

The lower feed roll shaft 20, as shown in Figure 10, has keyed to it a bevel gear 40 meshing with a bevel gear 42 fixed to a hub 44 fastened to the main drive shaft 46 which is journalled in a bushing in the casing 12. The upper feed roll shaft 22, as shown in Figure 4, carries a gear 48 driven from the lower feed roll shaft through the medium of a bevel gear 50 keyed to the lower feed roll shaft, the gear ratio and feed roll sizes being such that the upper feed roll is driven at a little faster speed than the lower feed roll and the two shafts being arranged at an acute angle.

As the strip S is delivered from the feed rolls, it passes through a guideway composed of a fixed guide plate 52 and a movable guide plate 54, the first plate being fastened by screws 56 to a block 58 which is fastened to the casing 12 by screws 60. The edges of the strip engage the guide plates and the sides of the strip engage right angular spaced extensions 62 and 64 formed on the guide plates 52 and 54 respectively. The movable guide plate has a recess at 66 engaging a holding projection 68 formed on a plate 70 fastened by means of screws 72 to a face plate 74 which in turn is fastened by the screws 60 to the block 58. The guide plate 54 is held against longitudinal movement by the projection and recess, and is adjustable widthwise of the strip by screws 78 passing through the plate 70 into the guide plate. Abutment screws 76 support the guide plate 54 and maintain the adjustment.

The guideway extends at an angle, less than a right angle, to a core member 80 having a flattened portion 92 to prevent it from turning in the block 58 and having also a cylindrical core 84 projecting from an end face 86, this face being inclined and preferably of helicoidal form, the face also having the same inclination as that of the guideway and forming in effect a continuation thereof. The core 84 extends into a recess 88 in the block 58, this recess containing a set of bending or winding rolls. These rolls 90, 92 and 94 are spaced about the axis of the cylindrical core and are equidistant therefrom. Each roll is keyed to a short driving shaft 96 journalled in a bushing in the block 58 and carrying a pinion

98 at one end for driving engagement with an internal gear 100 (see Figure 10) fastened to a cup-shaped holder 102 the hub 44 of which is fastened to the main drive shaft 46 by nuts 104. The other end 106 of each shaft 96 extends beyond the pinion and is here engaged by a thrust plate 108 which abuts against the end of a hand screw 110 threaded in the block 58 and secured in adjusted position by a lock nut 112. The rolls have to withstand considerable outward pressure from the material and the thrust plates prevent deflection. The bending rolls, as will be apparent, are so geared that they travel at a considerably greater speed than the feed rolls and they serve to bend and pull the strip bodily around and iron it against the core while the feed rolls exert a drag.

It should be noted that the bending roll 90 is arranged a little to one side of a line, normal to the path of feeding movement of the strip and passing through the core 84, and the roll first engages the strip on the outer side thereof as the strip is fed tangentially to the cylindrical core. Since the path of the outer face of the strip intersects the first roll 90, it is given an initial bend towards the center of the core after which the strip engages a surface on the end of a plate 114 of hardened steel. The plate 114 abuts at one end against the end of a hand screw 116 threaded in the block 58 and held in adjusted position by a lock nut 118 to provide for wear. A screw 120 in the face plate 74 engages an inclined side of the plate 114 to prevent the plate dropping into the path of the end of the strip. The end of the strip S is tapered to facilitate its bending both around the core and longitudinally of the core and, as the strip is progressively wound into a coil, it passes through a sleeve 122 fixed to the face plate 74 and having its interior inner end chamfered to guide the coil through the opening. The winding takes place in the recess 88 which is entirely closed, the strip itself closing the entrance opening through the guide plates 52 and 54 and also closing the exit opening through the sleeve 122.

As appears in Figure 3, the main drive shaft 46 of each winding head projects through the casing 12 or 14 and carries a limit collar 124, and an extension 126 of the shaft is keyed as indicated at 128 to receive a sliding clutch collar 130 (see Figure 1) which is moved longitudinally by a hand lever 132 pivoted to the clutch collar and to a bracket fastened on the stand. Each clutch member 130 has clutch teeth engaging cooperating clutch teeth on a clutch member 134 fixed to a stub shaft 136 journalled in a casing. Each shaft 136 carries a worm wheel 138 meshing with a worm 140 on a vertical worm shaft 142.

driven by a motor 144 supported on the base of the machine. The winding head in the casing 12 winds the strip left handed and the winding head in the casing 14 winds the strip right handed and the two strips may be simultaneously or independently wound. Both right and left hand coils are usually required because after the coils are cut up into lengths and incorporated in a roller bearing, the right and the left windings are arranged alternately in order to carry a supply of oil in both directions across the bearing.

In operation, a strip S of steel of rectangular cross-section, of any length and having its end tapered, is presented between the feed rolls 16 and 18 which cause the metal to flow slightly on the outside and give the strip a predisposition to form a helical coil. The strip then passes through the guide between the plates 52 and 54 and is presented tangentially to the cylindrical core 84 and at an angle, less than a right angle, to the axis of the core, this angle corresponding to the inclination of the helicoidal face 86. The taper on the end of the strip weakens it so that as the outer face of the strip meets the bending roll 90, it is given an initial bend towards the center thus causing the strip to engage the end of plate 114 and giving it a further bend towards the core axis. The strip next engages the second feed roll 92 which bends it still further so that it will coil around and meet the third bending roll 94 and continue to wind into a smooth cylindrical roll. The coil is thus progressively formed and can be made of any length desired and the length is not dependent upon the size of the machine.

Although the invention has been described by reference to a specific construction and series of steps, it should be understood that, in its broader aspects, it is not necessarily limited to the details selected for illustrative purposes.

I claim—

1. In a machine of the character described, a member fixed against rotation and having a reduced end, the portion of larger size having an end face of helicoidal form, means for continuously feeding a strip of material along said helicoidal face, and means spaced around the reduced end for bending the strip into a continuous coil; substantially as described.

2. In a machine of the character described, a member having a cylindrical core to receive a strip of material wound thereon, a set of winding rolls spaced about the core for winding the material, feed rolls, means for driving the feed rolls, and means for driving the winding rolls at a faster speed than the feed rolls; substantially as described.

3. In a machine of the class described, a member fixed against rotation and having a cylindrical core, a set of rolls spaced about the core, means for driving said rolls to wind the strip around the core, and means for exerting a drag on the material during the action of the winding rolls; substantially as described.

4. In a machine of the character described, a cylindrical core fixed against rotation, a set of rolls spaced about the core, and means for driving said rolls to pull a strip of material bodily around the core; substantially as described.

5. In a machine of the character described, a member having a cylindrical core and a helicoidal face, driven winding rolls spaced about the core, and means for guiding a strip of material at an angle to the axis of the core corresponding to the inclination of the helicoidal face; substantially as described.

6. In a machine of the character described, a member having a stationary cylindrical core, winding rolls spaced about the core, means for driving the rolls, and means for guiding a strip of material at an angle, less than a right angle, to the axis of the core; substantially as described.

7. In a machine for winding a rectangular strip of material into helical form, a feed roll having a concave periphery, a companion roll having a convex periphery, means for driving one of the rolls faster than the other, a cylindrical core to receive the strip, and means for bending the strip around the cylindrical core; substantially as described.

8. In a machine for winding a strip of material into helical form, a cylindrical core to receive the strip, means for bending the strip around the core, a feed roll having a concave periphery, and a companion roll having a convex periphery; substantially as described.

9. In a machine for winding a strip of material into helical form, a cylindrical core to receive the strip, means for bending the strip around the core, a feed roll having a concave periphery, a companion roll having a convex periphery, and means for driving one of the feed rolls faster than the other; substantially as described.

10. In a machine for winding a strip of material into helical form, a cylindrical core to receive the strip, means for bending the strip around the core, and a pair of feed rolls engaging opposite sides of the strip and delivering it to the bending means, the axis of one feed roll being at an acute angle to the axis of the other; substantially as described.

11. In a machine for winding a strip of material into helical form, a short cylindrical core to receive the strip, a series of plain rolls spaced about the core, means for driv-

- ing the rolls to drag the strip bodily around and iron it against the core, and means for encasing the rolls and the part of the strip in contact therewith; substantially as described.
12. In a machine for winding a strip of material into helical form, a cylindrical core to receive the strip, means for bending the strip around the core, a pair of feed rolls 10 engaging opposite sides of the strip and delivering it to the bending means, and means for driving the roll which engages the outer surface of the strip at a faster speed; substantially as described.
13. In a machine of the class described, a cylindrical core to receive a strip of material, means for presenting the strip tangentially to the core, a set of bending rolls spaced about the core, the first of said rolls 20 lying in the path of the outer side of the strip after the strip contacts with the core, and means for driving one or more of said rolls; substantially as described.
14. In a machine of the character described, a fixed cylindrical core to receive a strip of material, means for presenting the strip tangentially to the core, a roll lying in the path of the outer side of the strip after the strip contacts with the core, said roll 30 bending the strip inwardly, and a plate having a surface in the path of the strip as it is bent by the roll, said surface being parallel to the core for bending the strip around the core; substantially as described.
15. In a machine of the character described, a fixed cylindrical core to receive a strip of material, means for presenting the strip tangentially to the core, a roll lying in the path of the outer side of the strip after 40 the strip contacts with the core, said roll bending the strip inwardly, a plate having a surface in the path of the strip as it is bent by the roll, said surface being flat and parallel to the core for bending the strip around the core, and a second bending roll beyond 45 the plate; substantially as described.
16. In a machine for automatically winding a strip of material into helical form, a fixed cylindrical core to receive the strip of material, means for feeding the strip tangentially towards the core, and a roll lying in the path of the outer side of the strip, said roll and feeding means lying on opposite sides of a line normal to the direction of feed 50 and means for rotating the roll to drag the strip bodily around and iron it against the core; substantially as described.
17. In a machine for winding a strip of material helically into a hollow cylinder, a set of rolls having their peripheral faces 60 equally spaced from a common center, means for feeding the strip of material in a path extending at one side of said center and intersecting the first of said rolls, said first roll causing an initial bend of the material 65 and the remaining rolls completing the bend, and means for driving said rolls; substantially as described.
18. In a machine for winding a strip of material into a hollow cylinder, a cylindrical core, a set of rolls having their peripheral faces equally spaced from the core, means for feeding a strip of material in a path tangential to the core and intersecting the first of said rolls, said first roll causing an initial 70 bend of the material around the core, a helicoidal face at the base of the core for initially bending the strip in another direction, and means for driving the rolls; substantially as described.
19. In a machine of the character described, means for winding a strip of material into helical form comprising a cylindrical core and winding rolls, and means for guiding the strip to the core, said means comprising a pair of opposite plates having right angular spaced extensions to receive the strip; substantially as described.
20. In a machine of the character described, means for winding a strip of material into helical form comprising a cylindrical core and winding rolls, means for guiding the strip to the core, said means comprising a pair of opposite plates having right angular spaced extensions to receive the strip, and means for relatively adjusting said plates; substantially as described.
21. In a machine of the character described, means for winding a strip of material into helical form comprising a cylindrical core and winding rolls, and means for guiding the strip to the core, said means comprising a fixed plate to guide one edge of the strip, a movable plate to guide the other edge of the strip, and spaced extensions on the plates engaging the opposite sides of the strip; substantially as described.
22. In a machine of the character described, winding means, and means for guiding a strip of material to the winding means, said guiding means comprising a fixed plate having an angular extension, a head, a bracket fixed to the head and having a projection, a movable plate having a recess fitting said projection, said movable plate also having an angular extension, and adjusting means supported by the bracket and engaging the movable plate; substantially as described.
23. In a machine of the character described, a short core, a plurality of rolls arranged around the core for winding a strip of material thereon, and a sleeve to engage the outer surface of the wound strip as it comes from the core; substantially as described.
24. In a machine of the character described, a short core, a plurality of rolls arranged around the core for winding a strip of material thereon, and a sleeve to engage

the outer surface of the wound strip as it comes from the core, said sleeve having one end interiorly chamfered to guide the strip; substantially as described.

5 25. In a machine for winding a strip of material into helical form, a block having a recess, winding rolls rotatable in the recess, and a plate closing the end of the recess and having an exit opening closed by the wound strip; substantially as described.

10 26. In a machine for winding a strip of material into helical form, a block having a recess, winding rolls rotatable in the recess, a face plate closing the end of the recess and having an exit opening closed by the wound strip, and an entrance opening closed by the strip to be wound; substantially as described.

15 27. In a machine of the character described, a block, a cylindrical core supported by the block, drive shafts journaled in the block parallel to the core, a winding roll fixed to each shaft opposite the core, a pinion on each shaft, and an internal gear 20 for driving all of said pinions; substantially as described.

20 28. In a machine of the character described, a cylindrical core, a plurality of winding rolls spaced about the core, drive 30 shafts for the rolls, each of said shafts extending through its roll, and a thrust plate engaging each shaft beyond the roll; substantially as described.

25 29. In a machine of the character described, a block, a cylindrical core supported by the block, a shaft journaled in the block parallel to the core, a winding roll fixed to the shaft opposite the core, said shaft extending beyond the roll, and a thrust plate 35 engaging the end portion of the shaft; substantially as described.

30 30. In a machine of the character described, a set of winding rolls and a set of feed rolls, a drive shaft, an external gear 40 fixed to the drive shaft for driving the feed rolls, and an internal gear fixed to the drive shaft for driving the winding rolls at a faster speed than the feed rolls; substantially as described.

35 31. In a machine of the character described, a drive shaft, a set of winding rolls rotatable on axes parallel to the drive shaft, a pair of feed rolls rotatable on axes at an acute angle to the drive shaft, bevel gear 50 driving connections from the drive shaft to the feed rolls, and an internal gear fixed to the drive shaft for driving the winding rolls; substantially as described.

40 32. In a twin winding machine for strip 55 material, a frame, a pair of casings, winding instrumentalities in one casing for coiling a strip right handed, winding instrumen-

talities in the other casing for coiling a strip left handed, a shaft projecting through each casing, a drive shaft journaled on the frame, 65 stub shafts driven by said drive shaft, and independent clutches between the stub shafts and the shafts projecting from the casings; substantially as described.

5 33. In a twin winding machine for strip 70 material, a frame, a pair of casings, winding instrumentalities in one casing for coiling a strip right handed, winding instrumentalities in the other casing for coiling a strip lift handed, and means for simultaneously 75 or independently operating the winding instrumentalities; substantially as described.

10 34. The method of winding a strip of material into helical form in one operation 80 which consists in feeding the strip continuously along a helicoidal surface, and rolling the strip to bend it around a center; substantially as described.

15 35. The method of winding a strip of material into helical form which consists in 85 tapering the end of the strip, feeding it along a helicoidal surface, and rolling the strip to bend it around a center; substantially as described.

20 36. The method of winding a strip of material into helical form which consists in 90 feeding the strip along a helicoidal surface, rolling the strip to give it an initial bend towards a core, and again rolling the partially bent strip to pull it around the core; 95 substantially as described.

25 37. The method of helically winding a strip of metal into a smooth cylinder which 100 consists in tapering the strip, feeding the strip along a helicoidal surface, rolling the strip to give it an initial bend towards a center, and again rolling the partially bent strip to wrap it into a cylinder; substantially as described.

30 38. The method of winding a strip of material into helical form which consists in 105 feeding the strip tangentially and at an angle, less than a right angle, to a central core, and rolling the strip progressively to 110 pull it endwise around and iron it against the core; substantially as described.

35 39. The method of winding a strip of material into helical form which consists in 115 feeding the strip at an angle, less than a right angle, to a central axis, rolling the end of the strip to give it an initial bend towards the axis, and feeding the partially bent strip against an obstructing surface to bend it further towards the axis; substantially as described.

In testimony whereof I hereunto affix my signature.

HENRY S. WOODRUFF.
